UNITED STATES PATENT OFFICE

RALPH E. SMITH, OF GALION, OHIO, ASSIGNOR TO GALION METALLIC VAULT COMPANY,
OF GALION, OHIO, A CORPORATION OF OHIO

DUMP BODY

Application filed March 9, 1928. Serial No. 260,507.

My invention relates to dump bodies. It is the object of my invention to provide a dump body which can be elevated and lowered by a means which is flexible in one direction for telescoping and storing purposes, but which is inflexible in another direction for elevating purposes.

It is my object to provide such a means in combination with the power device, preferably driven from the engine of a truck for elevating the truck body.

It is a further object to provide means for automatically limiting the application of the power for elevating and for lowering the body so that each movement will be automatically terminated by disconnecting the power. Manual control is provided for applying this power for starting the elevating, but is so arranged as to not permit the elevating to be extended beyond a safe limit by the manual means. Likewise the lowering cannot be extended by the manual means beyond the safe lowering limit, but the manual means can start and stop the movement in either direction and can control the movement intermediate the starting and lowering limits.

Referring to the drawings:

Figure 1 is a side elevation showing the body in lowered position.

Figure 2 is a side elevation partially in section, showing the body in elevated position.

Figure 3 is a section on the line 3—3 of Figure 1.

Figure 4 is a section on the line 4—4 of Figure 3.

Figure 5 is a section on the line 5—5 of Figure 4.

Figure 6 is a detail plan view of the connection between the roller frame rod and the upward movement gear shifting rod.

Figure 7 is a section on the line 7—7 of Figure 3, showing the gear mechanism and gear shifting mechanism.

Figure 8 is a side elevation, in detail, of the pivotally mounted roller frame.

Figure 9 is a rear elevation thereof.

Figure 10 is a detail view of the clutch 50 collar.

Figure 11 is a section on the line 11—11 of Figure 10.

Referring to the drawings in detail, 1 represents supplementary side members connected by the bolts 2, which are in spaced relationship and are mounted upon the usual truck frame, attached thereto by any desired means such as U bolts, which are strapped around the supplementary frame members 1 and connected to the main frame. 55 These details do not form any part of the present invention but follow conventional practice.

Between these side members 1 extends pivot shaft 3, on which are mounted pivot brackets 65 on either side thereof, designated 4, the upper ends of which, as at 5, are attached to the frame member 6 of the truck body 7.

The forward end of this truck body, when in horizontal position, has its bottom frame member 6 resting upon the transverse angle iron members 8 and 9 located in spaced relationship transversely of the supplementary frame members 1 at the forward end thereof, adjacent the cab 10.

Between the supplementary frame members 1 carried on suitable transverse supports 11, is a trough 12 adapted to contain the elevating chain 13, which is telescoped therein. The forward end of this trough is turned 80 upwardly, as at 14. The transverse angle irons 8 and 9 are connected together by longitudinally extending, spaced frame members 15 and 16, being connected thereto by suitable bolts 17 and angle irons 18. The forward

end of the trough 14 is connected by the bolts 17 to the forward transverse frame member 9. 85

Mounted on these longitudinally extending frame members 15 and 16 are journal blocks 19 and 20 that are interconnected by the strap 21. In these journals there is carried the shaft 22, which is the driven shaft of the combination.

Mounted on this driven shaft is the chain 95 actuating pinion 23, which is adapted to engage with the teeth 24 of the chain links 25, which are connected together by the pivot bolts 26 passing through the projections 27 and the overlapping ears 28 of alternate adj-

cent chain blocks. Pivotedly mounted on either side of the pinion 23, on the shaft 22, are the side frame plates 29 and 30 of the swinging roller frame. The forward ends of these frames are interconnected by a guard plate 31.

Within this guard plate 31 is a pair of transverse roller shafts 32 and 33, carrying rollers 34 and 35 which engage with the rear smooth surface 36 of the chain blocks. These blocks are so arranged as to permit of movement towards each other in one direction but are prevented from movement toward each other in the other direction beyond a plane running through the longitudinal axes of the blocks so that in one direction the blocks, when so moved, present a stiff, rigid structure in a single plane, but in the other direction may be bent to follow around the rollers and pinion 23.

The lower end of these side frames 29 and 30, designated 36^a, carry a roller shaft 37 which in turn supports a roller 38 below the pinion 23 that engages the tooth side of the blocks of the chain, causing the blocks to make a substantially right angle turn about the center of the shaft 37 as the blocks move from the telescoping trough 12 in a horizontal plane to a vertical and substantially rearwardly extending plane necessary for the elevation of the forward end of the truck body, to which the upper block is pivoted in the following manner.

The upper block is pivoted to a bolt 39, which bolt is carried in the ears 40 between which the upper end of the block projects. These ears 40 are mounted upon a pivot block 41 adapted to have some lateral movement by reason of the cutaway portions 42, where the block is pivoted upon the shaft 43 carried in the ears 44 of the plates 45, which are bolted by the bolts 46 to the bottom of the forward end of the dump body.

This block 41 is provided with a depending finger 47 that serves to maintain the block in its proper predetermined position, as will be seen in Figure 4, so that it cannot buckle with respect to the next block and thereby permit the chain to buckle during the initial stages of elevating the body.

The purpose of pivotally mounting the roller frame side plates 29 and 30 is to permit of the movement of these plates and frame with the rollers to cause the chain to maintain itself in the same plane as a stiff elevating member, as the upper end of the chain moves backwardly due to the arcuate movement of the body, to which it is attached, which is remotely pivoted on the rod 3 at the rear end of the truck.

To insure this coordinated movement I have provided the following mechanism. The upper end of the frame is connected to a yoke 48, the pivoting being at 49. The free end 65 of this yoke is adjustably connected to a

rod 50, known as the roller frame rod, the rear end of which is connected to another yoke 51, which in turn is pivotally mounted upon an upstanding lever 52 that is rigidly attached to the pivot shaft 3 and moves with the truck body in its arcuate movement.

This roller frame rod 50 has attached to it rigidly a sleeve 53, which projects laterally, forming an eye 54. Through this eye 54 is projected a clutch shifting rod 55 having a head 56 adapted upon occasion of the body reaching its uppermost position to engage with the side 57 of the eye 54, so that the continued upward movement of the body serves to pull the upwardly moving clutch shifting rod 55, thereby bringing about a de-clutching of the power line and a cessation of upward movement on the part of the body.

This rod 55 is connected at its lower end to a bell crank, being pivotally connected at 58 to the bell crank arm 59, which is pivoted at 60 upon the gear casing 61. This arm 59 is also connected to the manually operated rod 62, which extends to a point adjacent the operator in the cab 10 in the usual manner.

This pivotal clutch shifting rod 60 is provided with a yoke 61^a within the gear casing 61, and a notch 63 in which fits a plunger 64, spring pressed by the spring 65 to maintain it in neutral, elevating or lowering positions. The yoke 61^a fits within a groove 66 of a collar 67, which has side shoulders 68 and 69 for engaging with the clutch pin 69^a of the respective bevel gears 70 and 71, which are driven by the bevel pinion 72 by the power shaft 73 from the truck motor.

This clutch sleeve 67 is mounted to turn with the shaft 74 and is splined thereon by the spline sleeve 75. The upper end of the shaft 74 is provided with a worm 76, which drives the worm gear 77, which is connected with a key 78 to the driven shaft 22.

When the truck body descends its bottom is adapted to engage with the top of the lowering movement clutch shifting rod 79, which is connected at its lower end to the arm 80 of the bell crank, of which the arm 59 is the other half.

Method of operation.

When the operator moves the rod 62 he throws the clutch so that the shaft 22 will be driven to elevate the roller chain through the pinion 23, and as this elevation takes place the frame gradually is tilted backwardly. This continues until the nut 56 on the rod 55 engages with the eye 54, causing the clutch to be shifted. Thereupon the operator can move the shaft 62 to throw the clutch into position for lowering the body, and this operation will continue until the bottom of the body comes in contact with the top of the rod 79, again shifting the clutch to neutral inoperative position.

If the operator, during the course of either the upward movement or the downward movement, desires to halt the movement or reverse its direction, he can do so by operating the rod 62.

I desire to comprehend within my invention such modifications as may be clearly embraced within the claims and the scope of my invention.

Having thus fully described my invention, what I claim is new and desire to protect by Letters Patent, is:

1. In combination, a supporting frame, a dump body pivoted thereon, means flexible in one direction and inflexible in another adapted to elevate said body, means for driving said means to raise and lower said body, and follow means for maintaining said elevating means in its stiff condition adapted to engage therewith to so maintain the elevating means, said follow means being pivotally mounted, and means connected therewith and to the truck body to synchronize the movement of the follow means with the movement of the body and the movement of the elevating means.

2. In combination, a frame, means for receiving an elevating means within said frame, a truck body pivoted on said frame, an elevating means flexible in one direction adapted to be telescoped within said frame and inflexible in the other direction for elevating the body, power means for actuating said elevating means from telescoping position to elevating position, follow means adapted to guide said elevating means relative to the power means and to maintain it in stiff condition as it moves upwardly and backwardly with the body, and means for moving said follow means in synchronism with the movement of the body.

3. In combination, a frame, a body pivotally mounted on one end thereof for dumping, means for elevating said body connected to the forward end adapted to be telescoped within said frame, flexible in one direction and inflexible in the other direction, means for actuating said elevating means, means to guide said elevating means to the actuating means, means to maintain the elevating means in inflexible condition and in engagement with the actuating means and to prevent its buckling, said guiding means and last-mentioned means being adapted to move as a unit.

4. In combination, a frame, a body pivotally mounted on one end thereof for dumping, means for elevating said body connected to the forward end adapted to be telescoped within said frame, flexible in one direction and inflexible in the other direction, means for actuating said elevating means, means to guide said elevating means to the power means, means to maintain the elevating means in inflexible condition and in engagement

with the power means and to prevent its buckling, said guiding means and last-mentioned means being adapted to move as a unit, and means to move said unit in synchronism with the movement of the body pivotally about the power means as applied to the elevating means.

5. In combination, a frame, a dump body pivoted on one end thereof, means to support an elevating chain, an elevating tooth and chain flexible in one direction and inflexible in the other direction, a pinion adapted to engage with the teeth of said chain, a pivotally mounted guiding frame having rollers on opposite sides of said chain adapted to guide said chain from its telescoped position to its elevating position as actuated by power means, power means consisting of a pinion in driving engagement with the teeth of the chain, said chain being held in engagement with said pinion by said rollers behind said chain carried by said guiding frame, and a link connecting said frame and said body so that as the chain moves upwardly and backwardly the frame will move with it.

6. In combination, a frame, a body pivoted thereon at the rear end thereof, means for carrying a flexible elevating toothed chain, a flexible elevating chain flexible in one direction and inflexible in the other direction, having its free forward end connected to the forward end of the body, a driving pinion adapted to engage with the teeth on said chain to elevate it, a guiding frame for said chain pivotally mounted, having a guiding roller to the rear of the chain below the pinion driving the chain to form a corner about which the chain in flexed condition will pass to the driving pinion into inflexed condition, and spaced guide rollers engaging the rear of said chain oppositely disposed from the driving pinion for maintaining the chain in inflexed condition at the pinion and beyond to prevent the buckling of the chain, and means for causing said frame with its rollers to move synchronously about the point of application of the power to said chain with the movement of the truck body.

7. In combination, a frame, a body pivoted thereon at the rear end thereof, means for carrying a flexible elevating toothed chain, a flexible elevating chain flexible in one direction and inflexible in the other direction, having its free forward end connected to the forward end of the body, a driving pinion adapted to engage with the teeth on said chain to elevate it, a guiding frame for said chain pivotally mounted, having a guiding roller to the rear of the chain below the pinion driving the chain to form a corner about which the chain in flexed condition will pass to the driving pinion in inflexed condition, and spaced guide rollers engaging the rear of said chain oppositely disposed from the driving pinion for maintaining the chain in

inflected condition at the pinion and beyond to prevent the buckling of the chain, means for causing said frame with its rollers to move synchronously about the point of application of the power to said chain with the movement of the truck body, and means connecting the upper end of the chain to the truck body pivotally while preventing the buckling of the chain during the initial stages of elevation of the body.

8. In combination, a frame, a body pivoted thereon at the rear end thereof, means for carrying a flexible elevating toothed chain, a flexible elevating chain flexible in one direction and inflexible in the other direction, having its free forward end connected to the forward end of the body, a driving pinion adapted to engage with the teeth on said chain to elevate it, a guiding frame for said chain pivotally mounted, having a guiding roller to the rear of the chain below the pinion driving the chain to form a corner about which the chain in flexed condition will pass to the driving pinion in inflexed condition, and spaced guide rollers engaging the rear of said chain oppositely disposed from the driving pinion for maintaining the chain in inflexed condition at the pinion and beyond to prevent the buckling of the chain, means for causing said frame with its rollers to move synchronously about the point of application of the power to said chain with the movement of the truck body, means connecting the upper end of the chain to the truck body pivotally while preventing the buckling of the chain during the initial stages of elevation of the body, said means consisting of a horizontally disposed link pivoted at one end to the body and at the other end to the chain having a limited movement out of the horizontal plane with respect to the body, and a shoulder on the bottom thereof for engaging the back of the first link of the chain.

9. In combination, a frame, a truck body pivoted thereon, means for supporting in telescoped position an elevating means connected with the forward end of the body, said elevating means consisting of a plurality of chain links toothed on one side and flat on the other side, flexible towards the toothed side and inflexible towards the flat side, a driving pinion adapted to move said elevating means in either direction when in inflexible position, a guiding means for guiding the chain from flexible position into driven inflexible position and for maintaining the chain in inflexible position at and beyond the driving pinion, a power means adapted to move the chain in either direction, a clutch for controlling said power means, means interconnecting said body and said chain, means to move said guiding means pivotally about the point of application of power to the chain, means associated therewith for disconnecting the

clutch at the end of the upward movement of the body, and means adapted to engage the bottom of the body to disconnect the clutch at the end of the lowering movement of the body.

10. In combination, a frame, a truck body pivoted thereon, means for supporting in telescoped position an elevating means connected with the forward end of the body, said elevating means consisting of a plurality of chain links toothed on one side and flat on the other side, flexible towards the toothed side and inflexible towards the flat side, a driving pinion adapted to move said elevating means in either direction when in inflexible position, a guiding means for guiding the chain from flexible position into driven inflexible position and for maintaining the chain in inflexible position at and beyond the driving pinion, a power means adapted to move the chain in either direction, a clutch for controlling said power means, means interconnecting said body and said chain, means to move said guiding means pivotally about the point of application of power to the chain, means associated therewith for disconnecting the clutch at the end of the upward movement of the body, means adapted to engage the bottom of the body to disconnect the clutch at the end of the lowering movement of the body, and manually operated means connected to said clutch to start the elevating and lowering operations and to control them intermediate the ultimate accomplishment of either one of said operations.

11. In combination, spaced supplementary frame members adapted to be mounted upon a truck, a body pivoted on the rear end thereof, a trough carried therebetween, means mounted thereon for supporting the forward end of the body, a driven shaft carried thereby having a pinion, an elevating chain flexible in one direction and inflexible in the other, adapted to be telescoped within said trough and to pass upwardly from the forward end of said trough adjacent its point of connection to the forward end of the body, a guiding frame mounted on said driven shaft pivotally having a guiding roller on the rear side of said chain below said driven shaft for causing the flexible chain to move from flexible position to inflexible position, and a pair of spaced rollers oppositely disposed from said pinion engaging the rear of said chain for maintaining the chain in inflexible position in driving engagement with the pinion, a gear box having gearing therein adapted to drive said driven shaft in either direction, a clutch therein adapted to determine the direction of movement of the driven shaft, an exteriorly located bell crank connected to said clutch, a guide frame rod connecting said frame and the rear end of said truck body, an eye

70

mounted on said rod, a clutch shifting rod slidably mounted in said eye for limiting the movement, connected at its free end to said clutch shifting bell crank to shift the clutch 5 when the end of the rod engages with the eye on the guide frame rod at the end of the upward movement of the body, and a second clutch shifting rod connected to said bell crank adapted to engage the bottom of the body when it descends to its lowermost position to stop the lowering of the body.

12. In combination, spaced supplementary frame members adapted to be mounted upon a truck, a body pivoted on the rear end thereof, a trough carried therebetween, means mounted thereon for supporting the forward end of the body, a driven shaft carried thereby having a pinion, an elevating chain flexible in one direction and inflexible in the other, 15 adapted to be telescoped within said trough and to pass upwardly from the forward end of said trough adjacent its point of connection to the forward end of the body, a guiding frame mounted on said driven shaft pivotally having a guiding roller on the rear side of said chain below said driven shaft for causing the flexible chain to move from flexible position to inflexible position, and a pair of spaced rollers oppositely disposed from said pinion engaging the rear of said chain for maintaining the chain in inflexible position in driving engagement with the pinion, a gear box having gearing therein adapted to drive said driven shaft in either 20 direction, a clutch therein adapted to determine the direction of movement of the driven shaft, an exteriorly located bell crank connected to said clutch, a guide frame rod connecting said frame and the rear end of said truck body, an eye mounted on said rod, a clutch shifting rod slidably mounted in said eye for limiting the movement, connected at its free end to said clutch shifting bell crank to shift the clutch when the end of the rod engages with the eye on the guide frame rod at the end of the upward movement of the body, a second clutch shifting rod connected to said bell crank adapted to engage the bottom of the body when it descends to its lowermost position to stop the lowering of the body, and means pivotally connecting the free end of the chain to the forward end of the body, having means to prevent the buckling of the chain adjacent the point of connection to the body.

In testimony whereof, I affix my signature.

RALPH E. SMITH.
